UNITED STATES PATENT OFFICE

WILLIAM CAMPBELL, OF TULSA, OKLAHOMA

COMBINATION LADDER AND IRONING BOARD

Application filed November 28, 1930. Serial No. 498,887.

This invention aims to provide a device which may be used either as an ironing board or as a step ladder, at the will of an operator, novel means being provided for holding the parts of the article in such shape that it may be used either as an ironing board or as a step ladder. Another object of the invention is to provide novel means for pivotally connecting the legs of the board to the platform, and for supporting the flat iron holder.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows in side elevation, a device of the kind hereinafter described, in use as an ironing board;

Figure 2 is a top plan;

Figure 3 is a transverse section;

Figure 4 is an end elevation;

Figure 5 is a vertical section showing the article set up for use as a ladder.

The device forming the subject matter of this application, comprises a platform 1 provided with a hole 2 in one end, by which the article can be hung up when not in use. A transverse cleat 3 is secured to the under side of the platform 1 and is located near to one end of the platform. Across the upper end of the platform extends a metal strap 4 which is in vertical alignment with the cleat 3. The strap 4 has downwardly extended, rectangular ends 5 (Figure 3) disposed parallel to the ends of the cleats 3. The cleat 3 is not quite so wide as the platform 1. A pivot rod 6 extends through the cleat 3 from end to end.

The numeral 8 marks a main leg includ-

ing side bars 7 connected by cross pieces 9. The upper ends of the side bars 7 of the main leg 8 are mounted to swing on the pivot rod 6, between the ends of the cleat 3 and the rectangular ends 5 of the metal strap 4.

The side bars 7 of the main leg 8 are connected by a rod 10 on which one end of a U-shaped brace 11 is mounted to swing, the opposite end of the brace being adapted to be engaged in a seat 12 on a keeper plate 14 secured to the under surface of the platform 1, the keeper plate having an additional seat 15, the use of which will be explained hereinafter.

Auxiliary legs 16 are provided, and are mounted to swing on the pivot rod 6, outwardly of the ends 5 of the metal strap 4, as Figure 3 will show. The pivot rod 6 is provided at its ends with enlargements 17 which cooperate with the auxiliary legs 16 to hold them in place for swinging movement in a direction at right angles to the axis of the pivot rod 6. One of the enlargements 17 retains a suspension member 18 in the form of a hook.

The auxiliary legs 16 are connected intermediate their ends by a metal tie 19 carrying a suspension element 23. The use of the suspension element will be explained hereinafter. The tie 19 is provided at its ends with rectangular flanges 20 which overlap the outer surfaces of the auxiliary legs 16, the flanges being secured to the said legs. The flanges 20 are provided at their inner edges with forwardly extended projections 21, which may be hooks. Braces 22 are pivoted at 24 to the side bars 7 of the main leg 8. At their lower ends, the braces 22 have seats 25 adapted to receive the projections 21 on the auxiliary legs 16.

As shown in Figure 3, a strip 26 of metal is secured at 27 on top of the strip 4 that extends cross wise of the platform 1. Intermediate its ends, the strip 26 is offset at 28 to form a socket, adapted to receive an underlying finger 29 on a flatiron support 30, in the form of a plate, disposed above the platform 1 and provided with an asbestos lining 31.

The general operation of the device, when in use as an ironing board, will be understood readily when Figure 1 of the drawings is noted. When it is desired to knock down the ironing board, the braces 22 may be cast off the projections 21, the braces 22 and the auxiliary legs 16 being folded into parallelism with the main leg 8. The upper end of the brace 11 is detached from the seat 12 of the keeper plate 14, the brace 11 is swung down into parallel relation to the main leg 8, and the platform 1 swings down on the main leg 8. The device, thus, is disposed in a small compass, when not in use. The suspension member 18 is used to carry a bucket of water or any other substance, used while cleaning operations are performed on the platform 1. Especial attention is directed to the metal strop 4 of Figure 3. This part has a double function. First, it affords an anchorage for the flatiron support 30; and secondly, its ends 5 form bearings for the pivot rod 6 which carries the auxiliary legs 16 and the side bars 7 of the main leg 8.

When the device is to be used as a ladder, it is set up, as shown in Figure 5. The side bars 7 become the stiles of the ladder, and the cross pieces 9 become the treads of a ladder. The platform 1 forms the prop for the ladder, the outer end of the brace 11 being engaged with the seat 15 on the keeper plate 14.

The auxiliary legs 16 are swung backwardly into the position shown in Figure 5, and are held in that position by engaging the seats 25 of the braces 22 with the projections 21 on the auxiliary legs 16. When the parts are arranged as shown in Figure 5, a bucket of water, a pot of paste, or anything of like kind, can be hung up on the suspension element 23 of the tie 19, within convenient reach of an operator.

The device forming the subject matter of this application is simple in construction but it affords a means whereby a person may have either an ironing board or a step ladder without being called upon to provide himself with two separate instrumentalities capable of functioning, respectively, as an ironing board and as a step ladder, a single structure accomplishing a double purpose.

Among other combinations, the device forming the subject matter of this application comprises a body 1, a main leg 8 and an auxiliary leg 16 having common pivotal connection at 6 with the body, a brace 11 forming a detachable connection between the body 1 and the main leg 8, and a second brace 22 forming a connection between the main leg 8 and the auxiliary leg 16, and located on one side of the body 1, when the body is in a substantially horizontal position, as shown in Figure 1, the auxiliary leg 16 being movable to an outstanding position on the opposite

side of the body 1, when the body is in a substantially vertical position, as in Figure 5, the second brace 22 being detachable from the auxiliary leg 16 when the body is in the first-specified position (of Figure 1), and being movable to engage the auxiliary leg again, when the body is in the second-specified position, that is, in the position of Figure 5.

Having thus described the invention, what is claimed is:

1. In a device of the class described, a body, main and auxiliary legs having a common pivotal connection with the body, a brace forming a detachable connection between the body and the main leg, and a second brace forming a connection between the main and auxiliary legs, and located on one side of the body, when the body is in a substantially horizontal position, the auxiliary leg being movable to an outstanding position on the opposite side of the body, when the body is in a substantially vertical position, the second brace being detachable from the auxiliary leg, when the body is in a horizontal position, and being movable to engage the auxiliary leg again, when the body is in a vertical position.

2. In a device of the class described, a body, a cleat on the body, a pivot member carried by the cleat, a strap extended across the top of the body and having rectangular ends which depend over the edges of the body, the pivot member being mounted in said depending ends, said ends being spaced from the ends of the cleat, a main leg mounted on the pivot member, between said ends of the strap and the ends of the cleat, auxiliary legs mounted on the pivot member, outwardly of said ends of the strap, a brace connecting the main leg with the body, and braces connecting the auxiliary legs with the body.

In testimony that I claim the foregoing as my own, I have hereto affixed my signature.

WILLIAM CAMPBELL.
